(57)

CLAIM

The ornamental design for an unmanned aerial vehicle, as shown and described.

DESCRIPTION

FIG. 1 shows a top perspective view of an unmanned aerial vehicle, illustrating our new design.

FIG. 2 shows a bottom plan view thereof.

FIG. 3 shows a front elevational view thereof.

FIG. 4 shows a rear elevational view thereof.

FIG. 5 shows a top plan view thereof.

FIG. 6 shows a bottom perspective view thereof; and,

FIG. 7 shows a side elevational view thereof.

The broken lines are for the purpose of illustrating portions of the unmanned aerial vehicle that form no part of the claimed design.
